UNITED STATES PATENT OFFICE

2,554,129

PIANO ACTION

Charles Frederick Stein, Ivoryton, Conn., assignor
to Pratt, Read and Company, Inc., Ivoryton,
Conn., a corporation of Connecticut

Application May 28, 1947, Serial No. 750,932

3 Claims. (Cl. 84—238)

1

This invention relates generally to piano actions and more particularly to a relatively simple action adapted for use with a piano having horizontally positioned strings.

In the prior art various attempts have been made to provide piano actions having down striking hammers for use in pianos having horizontal strings. These attempts have resulted in action structures which are relatively complicated and which are hard to get at to repair or adjust. Further, such actions have not been entirely satisfactory to provide a hammer which swings freely to strike a piano string with the required impetus and is then checked so that it does not bounce to again touch the string. It is also important that the action return to its position for operation quickly as required when fast passages are being played. In prior actions of this type, the response of the action to the touch of the person playing has been somewhat different than in standard upright and grand pianos making it difficult for a person accustomed to playing standard pianos to get the desired effects.

It is, therefore, an object of the present invention to provide an improved action for a horizontal piano which is of simple construction and which may be easily adjusted.

It is a further object of the present invention to provide an action for a horizontal piano having down striking hammers in which the characteristics of the action are substantially the same as that of accepted upright and grand piano actions.

A feature of the present invention is the provision of a simple piano action which requires a minimum of space and which is suitable for use in small pianos such as pianos adapted for portable use.

Another feature of the present invention is the provision of a piano key and action assembly in which adjustable spring means are provided for controlling the movement of the keys and hammers thereof.

A further feature of the present invention is the provision of a piano action including a hammer with a hammer butt which is operatively connected to the end of a piano key and which is spring biased to the normal position for operation by the key.

A still further feature of this invention is the provision of a piano hammer and a spring connected to the butt thereof which is arranged to apply the same force to restore the hammer to the normal position for operation regardless of the position of the hammer.

2

Further objects, features and advantages will be apparent from a consideration of the following description taken in connection with the accompanying drawings in which:

5 Fig. 1 is a perspective view of a piano showing the key and action assembly in accordance with the invention in position in the piano;

Fig. 2 is a cross-sectional view illustrating the key and action assembly;

10 Fig. 3 shows the key and action assembly of Fig. 2 in operative position;

Figs. 4 and 5 are detail views of springs used in the piano action;

Figs. 6 and 7 illustrate the normal and operative positions of a modified piano action; and

Figs. 8 and 9 illustrate the normal and operative positions of a still further piano action.

In practicing the invention, there is provided a piano action and key assembly including a key

20 frame on which the keys are supported and a fixed rail structure for supporting the piano action. The piano action includes hammers having hammer butts pivotally supported on the fixed rail structure and adapted to be operated by ex-

25 tensions provided on the piano keys. Individual springs are secured to the rail structure for biasing the keys to their normal positions. Adjustable means are associated with the springs for changing the tension thereof so that the pressure required to operate the key can be ad-

30 justed. Springs are also provided for holding the hammers in the normal positions for operation, these springs also being adjustable and being so arranged that the force exerted there-

35 by on the hammer is substantially constant for all positions of the hammer. A damper is also provided which is operatively connected to the butt of the hammer so that it is withdrawn from the spring when the action is operated.

40 Referring now to the drawings, in Fig. 1 there is illustrated a small horizontal piano 10 which is styled to correspond to a spinet desk. A string chassis 11 is provided in the piano including a frame which supports the strings and a sounding board. This structure is disclosed in

45 United States Patent No. 2,505,806, dated May 2, 1950. Supported on the string chassis 11 and extending substantially over the entire area thereof is a key and action assembly 12 including a plurality of keys 13 and actions 14 in ac-

50 cordance with the invention. The piano also includes a lyre structure 15 including pedals 16 for changing the expression of the action as will be further described. A music rack 17 is supported on a frame 18 extending across the rear portion of the keys 13. The case for the piano

includes a hinged top 19 which can be opened as shown to provide increased volume from the piano and provide access to the key and action assembly. The music rack is pivotally supported so that it can be turned forward and the cover 19 completely close the case.

Although the piano action in accordance with the invention may be used in any piano having horizontally positioned strings, it is particularly adaptable for use in a small piano such as disclosed in Fig. 1. In pianos actually constructed which include 64 keys, the entire piano may be only 38 inches wide and 23 inches deep and the operating structure of the piano can all be included in a case having a vertical dimension of approximately 7 inches. A single metal frame may be provided for supporting the strings and other operating components of the piano. When using a frame made of a light metal having a high tensile strength, such as an aluminum or magnesium alloy, the overall weight of a piano as illustrated is only about eighty pounds. Such an operating structure is obviously very easily portable and can be provided in a portable carrying case adapted to be carried by a person in the same manner as a large suitcase. Such a portable piano is disclosed and claimed in my copending application Serial No. 726,696 referred to above.

Referring now to Figs. 2 and 3, the piano key and action assembly is illustrated in operative position with respect to the string chassis 11. In these figures the string chassis 11 is shown as including a single metal frame 20, a pin block 21, a sounding board 26 and strings 23. The strings 23 are stretched between pins 22 in the pin blocks and pins secured to the frame 20 illustrated at 24 and 25. The sounding board 26 includes bridges 27 and 28 for engaging the strings in a well known manner. The frame 20 includes openings through which the bridges extend. Additional openings may be provided in the frame at points where the strain produced therein by the strings permits, to reduce the weight of the frame. For supporting the keys there is provided a key frame 30 which is secured to the metal frame 20 as by strips 31. The strip 31 at the front of the frame is shown in Fig. 2 and similar strips are provided at the sides of frame 20. The key frame includes the standard key mountings having pins 32 therein for guiding the keys 13.

The fixed rail structure includes a plurality of rails 35, 36, 37, 38 and 39, the rails being secured to the metal frame 20 as by brackets 40 shown in Fig. 1. The rail 35 is used for mounting a plurality of springs 41 which are arranged to hold the keys 13 in the normal position for the playing. A detailed view showing the configuration of the spring 41 is included as Fig. 4. Each spring 41 is held in position on the rail 35 by a screw 42 which passes through a washer 43 and loop 44 in the spring and is threaded into the rail. The end of the spring 41 rests on a ridge 35a and by adjusting the screw 42 the tension of the spring 41 is changed. This changes the force required to depress the piano key 13.

The piano action includes a hammer 45 having a head 46 and a butt portion 47 which is pivotally supported on the rail 36. The hammer butt 47 includes an extension 48 having a screw 49 adjustably positioned therein. Each of the keys 13 includes a rear extension 50 which is arranged to engage the head of the screw 49 to provide a direct connection between the key and hammer. Felt or other resilient material may be provided on the extension 50 of the key which engages the

screw 49. For holding the hammer in the normal position, there is provided a spring 51 which is adjustably supported on rail 37 in substantially the same manner that spring 41 is supported on rail 35. The configuration of this spring is shown in detail in Fig. 5. The tension in spring 51 can be changed by screw 52 which is adjustably positioned in the rail 37. The spring is positioned in a slot in the rail 38 which forms a guide therefor as illustrated at 53 in Fig. 1.

The piano action also includes a plurality of dampers 55 which are pivotally mounted on a fixed rail 39 and include heads 56 made of resilient material which normally bear against the piano strings 23. For raising the dampers from the strings, hooks 57 are provided which are connected to flexible cord 58 anchored in the hammer butt 47. As the hammer butt is rotated by the extension 50 of the key, the flexible cord and hook 57 cause the damper to be raised and the head thereof removed from the string. Provisions are also made for raising the dampers by the foot pedal mechanism. This arrangement includes a movable rail 60 pivotally supported on the fixed rail 39 and adapted to be moved upward by rod 61 which is operated by mechanical linkage 62 connected to the pedals 16 as shown in Fig. 1. When movable rail 60 is moved upward, all the dampers 55 connected with the various strings 30 are removed from the strings permitting the strings to vibrate freely. A spring 59 is secured to the fixed rail 39 and tends to hold the damper in the position in which the head 56 thereof engages the string 23.

In Fig. 3 there is illustrated the piano action of Fig. 2 with the various components thereof shown in the actuated position. As the key 13 is depressed, extension 50 thereof is raised and bears against the head of the screw 49 causing the hammer butt 47 to be rotated in a counter-clockwise direction and the head 46 of the hammer to be moved to a position closely adjacent the string 23. Although the hammer is not positively rotated to such a position that the head 46 thereof actually touches the string 23, the momentum of the hammer causes the movement to continue until the head strikes the string causing the string to vibrate. The hammer is then returned by spring 51 to the position where the screw 49 engages the extension 50 of the key which engagement checks the movement of the hammer. As shown in Fig. 5 the spring 51 includes a loop 63 and end portions 64 and 65 which extend at right angles with respect to each other. This spring provides substantially uniform tension on the hammer butt 47 regardless of the particular position of the hammer in its striking movement. By comparison of Figs. 2 and 3, it can be seen that although the tension in spring 51 is increased due to the upward movement of the hammer butt 47 this is counteracted by the forward motion of the hammer butt which tends to reduce the tension of the spring. As previously stated, the movement of the hammer butt 47 by the key causes the damper to be raised so that the head 56 thereof is removed from the string 23. The head 56 on the damper remains in this position until the key 13 is released at which time the various components of the action are restored to the position shown in Fig. 2.

As is apparent from Fig. 1, the screws 42 and 52 for adjusting the tension of the springs 41 and 51, respectively, are positioned so that they are available without dismantling the piano in any manner. The springs 41 are adjustable to

change the force required to operate the keys and, of course, can be set to provide the touch desired by any particular person. The springs 51 are adjustable to provide the tension required for returning the hammers 45 to the normal position for operation and yet allow the hammer to swing relatively freely to strike the string with the necessary impetus to produce a clear tone. The action of the damper 55 can be adjusted by bending the hook 57 so that the damper is removed from the string 23 at just the right moment.

Referring now to Figs. 6 and 7, there is illustrated in these figures a modified piano action in which a whip and jack mechanism furnishes the operative connection between the key 13 and the hammer 45. In this structure a whip 70 is pivotally supported on rail structure 36, being pivotally connected to a bracket 71 which also supports the hammer butt 72. A jack 73 is pivotally mounted on the whip 70 and includes a top edge 74 arranged to engage the rounded surface 75 on the hammer butt 72. The jack 73 includes a screw 76, the head of which engages the surface 77 of the hammer butt 72 for a purpose to be explained. A spring 83 is secured to the whip 70 and includes a portion 84 engaging the jack 73 for holding the jack against the hammer butt. For providing a check for the hammer, a pin 78 is connected to the whip 70 and extends in an opening 79 in a rear projection 80 of the hammer butt 72. For transmitting the movement of the key 13 to the action, a screw 81 is provided in the whip 70 having a head 82 which engages the extension 50 of the key 13. The key 13 and hammer 45 are held in the normal position for operation by springs 41 and 51, respectively, identical in every respect to the springs disclosed in Fig. 2. A damper 55 is also provided as in the previous modifications, the damper in this instance being operatively connected to the whip 70 by a hook 85 anchored in the whip and extending in an opening 86 in the body portion of the damper. The head 56 of the damper is held against the string 23 by a spring 59 as previously described.

Referring now to the operation of the structure of Figs. 6 and 7, as the key 13 is depressed the extension 50 thereof moves upward causing the whip 70 to be rotated in a counter-clockwise direction. This movement is transmitted through the jack 73 to hammer butt 72 causing the hammer 45 to also rotate in a counter-clockwise direction. As is apparent in Fig. 7, as the whip is rotated the engagement of screw 76 in the jack with the surface 77 of the hammer butt causes the jack to be pushed away from the hammer butt and the edge 74 thereof to be moved clear to the rounded surface 75. This frees the hammer from the jack. As in the structure of Fig. 2, the hammer 45 is rotated by the action mechanism until it very closely approaches the string 23 so that the momentum of the hammer causes the rotation to continue until the head 46 of the hammer actually strikes the string 23. The hammer 45 is then moved toward the normal position by spring 51, the motion of the hammer being checked by engagement of the pin 78 with the end 79a of the slot 79 as shown in Fig. 7. When the key 13 is released by the person playing, the projection 50 thereof moves downward and the whip 70 is released so that the hammer 45 can return to the normal position for operation as shown in Fig. 6. The spring 83 then moves the jack 73 to the position in which the

edge 74 engages the rounded surface 75 of the hammer butt so that the action is ready for a successive operation. As is apparent in Fig. 7 the upward movement of the whip 70 causes the damper 55 to be lifted off the string due to action of the hook 85 which engages the lower surface of the damper.

The adjustment of the springs 41 and 51 in the action of Figs. 6 and 7 is identical to that in the action of Figs. 2 and 3 and it is obvious that when this action is used in a piano as illustrated in Fig. 1, these adjustments are readily available from the top of the piano. The action of the damper 55 can be changed by bending the hook 85 in a manner well known.

In Figs. 8 and 9 there is illustrated a piano action which embodies a still further construction. This action is similar to the action of Fig. 2 with the exception that the spring 51 is eliminated and a spring 90 is provided instead. The spring 90 is secured to a bracket 91 on which the hammer butt 47 is pivotally supported and is connected to the hammer butt 47 by a flexible cord 92. The spring 90 holds the hammer 45 against the stop 93 in position for the operation by key 13. It is noted that this provides a much simpler arrangement than the structure of Fig. 2 as the spring 90 is relatively short so that guiding means such as a rail 38 is not required. The damper 55 is secured to the hammer butt 47 by a hook 57 and cord 58 in exactly the same manner as in Fig. 2.

In Fig. 9, the action is shown in the operated position with the hammer head 46 positioned close to the string 23. As in the prior modifications the momentum of the hammer will cause the head to continue until it strikes the string 23 causing the string to vibrate. The hammer 45 is then returned by the spring 90 until the screw 49 engages the extension 50 of the key to thereby check the movement of the hammer. Upon release of the key 13, the hammer 45 is rotated in a clockwise direction by the spring 90 until it engages the fixed rail 93. As the spring 90 is a simple leaf spring the tension therein increases as the hammer 45 is rotated. This effect, however, is slight and, due to the extreme simplicity of the action, it is very satisfactory in many instances.

In each of the structures disclosed, the keys 13 can be removed from the action without affecting the adjustment thereof. This is sometimes necessary in repairing and adjusting the assembly. The individual units of the action, that is, the hammers, dampers, etc., are also individually removable making for easy servicing of the action.

From the foregoing description, it is seen that I have provided an improved piano action and key assembly having a down striking hammer which is adapted for use with a horizontal piano. The end-to-end relation of the key and hammer provides a shallow assembly making possible a horizontal operating structure having a very small vertical dimension. It is obvious that such a structure is required in a piano as illustrated in Fig. 1. Means are provided for adjusting the action to provide the desired operating characteristics and as previously stated the springs controlling the keys can be adjusted to provide the touch desired in any particular instance. The adjusting means are readily available making for easy adjustment of the action.

Although I have described certain embodiments of my invention, it is apparent that

various changes and modifications can be made therein without departing from the intended scope of the invention as defined in the appended claims.

I claim:

1. A piano key and action assembly comprising a fixed rail structure, a hammer including a butt pivotally mounted on said rail structure, a whip pivotally mounted on said rail structure, a jack pivotally supported on said whip, a spring for holding said jack against said hammer butt, a key frame, a piano key supported on said key frame and having a rear extension positioned to engage said jack, a second spring secured to said fixed rail structure and engaging said key, means for adjusting the tension of said second spring for controlling the force required to operate said key, and a third spring secured to said fixed rail structure and engaging said hammer butt for holding said hammer in the normal position to be actuated by said key.

2. A piano key and action assembly comprising a fixed rail structure, a hammer including a butt pivotally mounted on said rail structure and having a projection thereon, a key frame, a piano key supported on said key frame and having an integral rear extension directly engaging said projection on said hammer butt, a spring secured to said rail structure and engaging said hammer butt to hold said hammer butt in engagement with said rear extension for operation of said hammer by said key, and means for adjusting the tension of said spring for controlling the operation of said hammer.

3. A piano key and action assembly comprising fixed rail structure, a hammer including a butt pivotally mounted on said rail structure, a key frame, a piano key supported on said key frame and including a portion operatively connected to said hammer butt, a spring secured to said fixed rail structure and connected to said hammer butt for holding said hammer in the normal position to be actuated by said key, said fixed rail structure including a rail having a slot therein, said spring being positioned in said slot to be guided thereby.

CHARLES FREDERICK STEIN.
